HIS ATTORNEY

UNITED STATES PATENT OFFICE

2,494,897

LAMP HOLDER

Edward B. Noel, Cleveland Heights, Ohio, assignor
to General Electric Company, a corporation of
New York

Original application April 27, 1944, Serial No.
532,938. Divided and this application May 11,
1946, Serial No. 669,144

3 Claims. (Cl. 240—37)

1

My invention relates to lamp holders for a plurality of flash lamps. This application is a division of the copending application Serial No. 532,938, filed April 27, 1944, by August W. Seitz and myself.

An object of my invention is to provide a lamp holder useful in the multiple flash device disclosed in the copending application referred to above. Another object of my invention is to provide a lamp holder having sockets for radially supporting a plurality of flash lamps in a common plane which holder is provided with electric contacts disposed on opposite sides of the said plane and which may be rotated about an axis perpendicular to the common plane to bring successively pairs of contacts into engagement with circuit contacts for flashing the lamps and the respective lamps into position to be flashed. Further objects and advantages of the invention will appear from the following detailed description of species thereof and from the appended claims.

In the drawing accompanying and forming part of this specification an embodiment of my invention is shown in which Fig. 1 is a side elevational view of a lamp holder embodying my invention and a turret supporting the holder and a fragmentary, partly sectional view of the reflector and the support member of the multiple flash lamp device of the aforesaid copending application; Fig. 2 is a top plan view of the holder shown in Fig. 1; Fig. 3 is an enlarged, partly sectional view of a socket part of the lamp holder and Fig. 4 is an enlarged, fragmentary, perspective view of the lamp base end of a flash lamp insertable in the socket of Fig. 3.

Referring to the drawings the lamp holder 1 is shown mounted on a turret 2 which is mounted so as to slide along a support 3 to which is fastened a bracket arm 4 supporting the reflector 5. The reflector 5 is concave and may be parabolic and has an opening at its vertex through which a flash lamp 6 mounted in the holder 1 may be moved into and out of the reflector 5. The holder 1 is mounted so as to revolve with the turret 2 and is adapted to support four lamps 6 disposed 90° apart. The lamps 6 in the holder 1 may be inserted successively into the reflector 5 by sliding the turret 2 along the support 3 and away from the reflector to withdraw a lamp 6 completely from the reflector, turning the turret 90° to bring another lamp into position to pass through the reflector opening and sliding the turret 2 back toward the reflector

2

5 to move the lamp replacement into the reflector and into position to be flashed.

A pair of contacts 7 and 8 for engaging contacts on the holder 1 and supplying current to flash the lamps 6 is mounted on the annular part 9 of the bracket arm 4 supporting the reflector 5 and in opposing positions with respect to the reflector opening. The upper contact 7 is secured directly to the said annular part while the lower contact 8 is electrically insulated therefrom. The lower contact 8 may be connected by an insulated lead 10 to one terminal of an electric battery contained in a battery case (not shown) fastened to the support 3. The upper contact 7 may be connected to the other terminal of the battery through the metal parts of the device and the battery case as described in the copending application. A conventional manually or automatically controlled switch may be used for controlling ignition of the lamp 6 in the reflector 5 so that the flash of the lamp may be synchronized with the opening of the camera shutter.

The lamp holder 1 comprises four lamp actuating sockets 13 facing in four different directions as shown in Fig. 2. Each of the sockets 13 accommodates a lamp base 14 of the type shown in Fig. 4 and which is disclosed in the Fulton and Foote application Serial No. 461,578 filed October 10, 1942, which issued July 22, 1947, as Patent 2,424,446 and is assigned to the assignee of this application. The lamp base 14 is cup-shaped and has a cylindrical rim 15, a disc-like web 16 and a pair of contacts 17 and 18 on the web 16. The contacts 17 and 18 are eccentrically mounted on the web with the contact 18 more eccentric than contact 17. The socket 13 comprises a plurality of annularly arranged spring fingers 20 the free ends of which slip over the edge or rim of cylindrical part 15 of base 14 when the latter is pushed into the socket 13 to hold the base contacts 17 and 18 firmly against socket contacts 21 and 22, respectively. The socket contact 21 is cylindrical and is yieldingly supported in the center of the socket 13 by a resilient electrical conductor 23 one end portion of which is bent over and bolted to an elongated insulating support member 24. The socket contact 22 is a helically coiled wire having a circular, free end and which is secured at its opposite end to the bottom of the spring fingers 20 which form a continuous cup-shaped surface which, in turn, is secured to an electrical conductor 25. One end portion of conductor 25 is bent over the other end of support

24. Contact 21 is spaced from the other electrically conducting parts of the socket 13 except conductor 23. Conductor 25 is spaced from conductor 23 to prevent short circuits between these elements. When the sockets 13 are mounted in the holder 1 the bent-over portions of conductors 23 and 25 are exposed and constitute contacts for engagement with the circuit contacts 7 and 8 on reflector bracket 9 as shown in Fig. 1.

The holder 1 has an aperture or passage 28 therethrough (Fig. 2) for accommodating the spindle 29 of the turret 2 and cavities 30 for accommodating part of pin 31 on the turret. Pin 32 on disc 33 of the turret may be used to turn the disc 33 and the holder 1 in replacing a flashed lamp 6. The holder 1 is hollow and is separable into two electrically insulating parts along the line 34 of Fig. 1 which parts are held together by removable bolts 35 (Fig. 2). The conductors 23 and 25 and the ends of member 24 pass through slots 36 in each part of holder 1. The mid-portion of member 24 is of greater width than the end portions thereof in slots 36 so that shoulders 37 are formed where the width of member 24 changes. The shoulders 37 abut against the inner surface of the hollow holder 1 to hold the socket 13 in proper position in said holder.

It will be understood that the lamp holder may be used with other types of multiple flash apparatus. For example, the lamp holder may, with slight modification, be used in apparatus similar to that disclosed in the John J. Malloy application Serial No. 508,480, filed November 1, 1943, now Patent 2,408,469, issued October 1, 1946, and assigned to the assignee of this application. In the aforesaid Malloy application the reflector is moved out of the path of the lamps when the lamp holder is rotated.

The lamps 6 are of the type disclosed in the Fulton and Foote application identified above and comprise beads of combustible material, such as those disclosed and claimed in the Pipkin Patent #2,291,983, issued August 4, 1942, supported in the bulb by a pair of current inleads which are bridged by an incandescent filament in contact with the said beads to ignite the latter. The lamps 6 are filled with a combustion supporting atmosphere, such as oxygen or air, at atmospheric pressure or lower and, when ignited, emit actinic radiation useful in taking photographs.

What I claim as new and desire to secure by Letters Patent of the United States is:

1. A lamp holder comprising an electrically insulating support block having a recess in one of its faces and a pair of internal passages extending from and transversely to the recess to the outside of the block, a socket for a lamp base mounted in the recess, a strip of insulating material extending transversely through said recess and along said passages and spaced electrical conductors attached to said strip and to said socket for holding said socket in said recess and extending from said socket through said passages to the outside of said block for engaging the ter-

minals of a power source for the lamp, said block being separable longitudinally of the recess and transversely of the passages for insertion and removal of the socket.

5 2. A lamp holder comprising an electrically insulating support having a recess and a pair of passages extending transversely to and in opposite directions from the recess to the outside of the support and a socket assembly mounted in said recess and said passages and comprising a strip of insulating material extending along both of said passages and across the inner portion of said recess, elongated electrical conductors mounted in spaced relation on opposite sides of said strip and extending in opposite directions from said recess with their outer end portions bent over and fastened to the ends of said strip and exposed outside said support for engaging circuit contacts, electrical contacts mounted on 10 the inner portions of said conductors and extending into said recess and a socket member also mounted on one of said conductors and supported thereby around said contacts in said recess and having spring fingers for receiving and gripping a lamp base to hold said base against said contacts.

15 3. A lamp holder comprising an electrically insulating support having a recess and a pair of passages extending transversely to and in opposite directions from the recess to the outside of the support and a socket assembly mounted in said recess and said passages and comprising a strip of insulating material extending along both of said passages and across the inner portion of said recess, elongated electrical conductors mounted in spaced relation on opposite sides of said strip and extending in opposite directions from said recess with their outer end portions bent over and fastened to the ends of said strip and exposed outside said support for engaging circuit contacts, electrical contacts mounted on the inner portions of said conductors and extending into said recess and a socket member also mounted on one of said conductors and supported thereby around said contacts in said recess and having spring fingers for receiving and gripping a lamp base to hold said base against said contacts, said support being separable longitudinally of said recess and transversely of said passages for insertion and removal of said socket assembly.
